UNITED STATES PATENT OFFICE.

MARTIN PANIAN, OF EVELETH, MINNESOTA.

SECURING MEANS FOR HEELS.

Application filed March 14, 1922. Serial No. 543,747.

To all whom it may concern:

Be it known that I, MARTIN PANIAN, a citizen of the United States, residing at Eveleth, in the county of St. Louis and 5 State of Minnesota, have invented a new and useful Securing Means for Heels, of which the following is a specification.

This invention aims to provide a novel staple which is so constructed that it may be 10 driven conveniently.

In the accompanying drawings:—

Figure 1 shows in bottom plan, a heel adapted to be held in place by the device forming the subject matter of the invention; 15 Figure 2 is a section on the line 2—2 of Figure 1; Figure 3 is a sectional view showing the auxiliary heel mounted on a main heel; Figure 4 is an elevation of the securing element or staple; Figure 5 is an elevation 20 wherein the securing element is viewed edge-wise; and Figure 6 is a perspective view showing a portion of the tool whereby the staple is driven.

The drawings show an auxiliary heel 1, 25 which, preferably, is made from rubber, the ground-engaging surface of the heel 1 being provided with bosses 2 and the upper surface of the heel 1 being supplied with depressions alined with the bosses 2. In the 30 bosses 2 and in the heel 1, elongated seats 4 are fashioned. There are spaced reduced openings 5 in the heel 1, the openings extending through the heel, and being located at the bases of the seats 4.

The auxiliary heel 1 is adapted to be secured on a main heel 15 through the instrumentality of staples, each including legs 6 connected by a bridge 7, the bridge having a longitudinal seat 8, and being provided 35 with a transverse seat 9 intersecting the seat 8.

For the driving of the staple, there is provided a tool as shown in Figure 6, the

tool including a body 10 having a longitudinal rib 11 at one end, and having, also, 45 a transverse rib 12. The longitudinal rib 11 of the tool is received in the longitudinal seat 8 of the bridge 6 of the staple, and the transverse rib 12 of the tool is received in the transverse seat 9 of the bridge of the 50 staple. The rib 11 and the corresponding seat 8 cooperates to prevent the tool from slipping transversely of the bridge 7 of the staple, the transverse rib 12 and the corresponding seat 9 coating to prevent 55 the tool from slipping longitudinally of the bridge of the staple.

In practical operation, the legs 6 of the staple are inserted into the openings 5, the staple being driven into the main heel 15, as 60 indicated in Figure 3, the bridge 7 being received in the seat 4. When the staple is driven home, the depressions 3 are flattened out, as shown in Figure 3, and the seats 4 are closed, as indicated at 65 14, the ground-engaging surface of the auxiliary heel 1 then being smooth as shown in Figure 3.

Having thus described the invention, what is claimed is:

1. A staple including legs and a bridge connecting the legs, the bridge being provided on its outer surface with a grooved longitudinal seat.

2. A staple including legs and a bridge 75 connecting the legs, the bridge having a grooved longitudinal seat, and being provided with a grooved transverse seat intersecting the first specified seat.

In testimony that I claim the foregoing 80 as my own, I have hereto affixed my signature in the presence of two witnesses.

MARTIN PANIAN.

Witnesses:

VICTOR E. ENLING,
KNUTE K. WALTI.
